UNITED STATES PATENT OFFICE.

HOWARD G. BROCKWELL AND LEWIS W. HENDERSON, OF RICHMOND, VIRGINIA,
ASSIGNORS TO THE KENTUCKY TOBACCO PRODUCT COMPANY, A CORPORATION
OF NEW JERSEY.

METHOD AND MEANS FOR REMOVING FOREIGN MATERIAL FROM TOBACCO-SCRAP.

1,164,986.

Specification of Letters Patent. Patented Dec. 21, 1915.

Application filed February 17, 1914. Serial No. 819,138.

To all whom it may concern:

Be it known that we, HOWARD G. BROCKWELL and LEWIS W. HENDERSON, citizens of the United States, residing at Richmond, county of Henrico, and State of Virginia, have invented certain new and useful Improvements in Methods and Means for Removing Foreign Material from Tobacco-Scrap, fully described and represented in the following specification and the accompanying drawings, forming a part of the same.

This invention relates to an improved method and apparatus for removing from tobacco scrap the foreign material, such as stem shreds, fiber, feathers, paper, etc., which heretofore has been picked from the tobacco scrap by hand. We have discovered that such foreign material may be largely removed from tobacco scrap by surface contact of a roll, or preferably a plurality of rolls, provided with a surface of material acting to pick up the foreign material from the tobacco scrap, and that a surface of the foreign material itself is excellently adapted for this purpose, so that the rolls may be used until they have accumulated a layer of such thickness as desired, this loose layer of foreign material then stripped off, and the roll used again. The tobacco scrap is preferably fed past the rolls instead of running the rolls over the tobacco, and this may well be done by carrying the tobacco scrap in a uniform layer on a feeding belt or other table moving below the rolls, and preferably suitable stirrers, such as suspended chains, or the like, with their free ends lying on the belt, will be used between each pair of rolls, so as to stir up the tobacco scrap and bring a fresh surface to the top after the tobacco layer has been partially cleaned by the preceding roll.

For a full understanding of the invention, a detailed description of a construction embodying the same will now be given in connection with the accompanying drawings, and the features forming the invention then specifically pointed out in the claims.

In the drawings, Figure 1 is a sectional side elevation of a simple form of apparatus embodying the invention. Fig. 2 is a plan view of the same. Fig. 3 is an enlarged cross section on the line 3—3, Fig. 1, showing a roll in operation; and Fig. 4 is a section of

Fig. 3 taken longitudinally of the feeding belt.

Referring to the drawings, *a* is a moving table for feeding the tobacco scrap forward, shown as a belt mounted on rollers 10, and driven by any suitable means, the tobacco scrap being fed onto the rear end of this belt from a chute or by hand, in any suitable manner, as common with picking belts. Above the belt *a* are mounted a series of rolls *b*, three being shown in the present case, although less or more may be used if desired, these rolls *b* being mounted in any suitable manner so as to be free to move away from the belt as the layer of foreign material thereon increases in thickness. In the construction shown, these rolls are simply slipped into vertically slotted supports 11, in which the rolls are free to move vertically. Between each pair of rolls *b* are mounted stirrers *c*, which in the form shown consist of metal chains arranged in series across the belt and suspended from a bar 12 carried by supports 13 on opposite sides of the belt, so that the ends of the chains *c* rest upon the belt, and drag through the tobacco scrap as the latter is carried forward by the belt, thus stirring up the tobacco and bringing a fresh surface to the top for action of the next roll thereon.

The rolls *b* may be made in any desired manner and provided with any surface suitable to pick up foreign material from the scrap tobacco. With any such surface, the operation of the roll at once forms a layer of foreign material upon the roll, and this foreign material is very efficient for the purpose desired. The roll, therefore, preferably is formed with such a surface, and in practice we have used a light wooden roll about an inch in diameter, and prepared this by coating it with glue and covering it with a thin layer of the shreds and fiber which are to be picked up from the tobacco scrap, this layer being stuck on by the glue. The drawings show a roll thus formed, 1 being the center wooden roll and 2 being the layer of shreds, fiber, etc., glued on the roll.

The operation of the construction will be understood from a brief description. The tobacco scrap *a*, fed onto the rear end of belt *a* in a uniform layer, is carried forward by the belt beneath the successive rolls *b* which rotate freely in their bearings and,

as they are rotated by the moving tobacco on the belt, pick up from the top of the tobacco the foreign material such as above described, the rolls being light and free to move upward, so as to increase the distance between them and the belt, as the layers of foreign material on the rolls increase in thickness. After the tobacco *x* passes the first roll *b*, it is stirred by the chains *c* so as to bring a new surface to the top for the action of the second roll *b* and so on with the successive rolls and chains, the cleaned tobacco being finally delivered from the end of the belt *a*. In practice, it is found that the rolls may be run up to a diameter of 12 inches or more, when the roll is removed from the table and the foreign material stripped off down to the original material held on by the glue, and the roll is then again ready for use and is returned to its bearings over the belt. In Figs. 3 and 4, one of the rolls is shown operating on the tobacco *x* upon the belt *b*, with a layer of foreign material *y* of considerable thickness picked up by the roll.

It is found in practice that the foreign material collected by the rolls *b* and thus removed after they have attained a convenient size, contains practically no tobacco, and that the tobacco delivered by the belt is largely cleaned from foreign material such as described.

It will be understood that the invention is not to be limited to the specific construction or arrangement of parts illustrated, but that widely different constructions may be used within the invention as defined by the claims.

What is claimed is:

1. The method of removing the foreign material, such as shreds, fiber, etc., from tobacco scrap, which consists in rotating over the surface of a layer of scrap one or more rolls having a surface adapted to pick up such foreign material from the tobacco scrap and maintaining the proper distance between the scrap and roll surfaces by relative movement of the roll and scrap away from each other as the layer of foreign material on the roll increases in thickness.

2. The method of removing the foreign material, such as shreds, fiber, etc., from tobacco scrap, which consists in moving the tobacco scrap in a uniform layer past and in contact with one or more rotating rolls having a surface adapted to pick up such foreign material from the tobacco scrap and maintaining the proper distance between the scrap and roll surfaces by relative movement of the roll and scrap away from each other as the layer of foreign material on the roll increases in thickness.

3. The method of removing the foreign material, such as shreds, fiber, etc., from to-

bacco scrap, which consists in moving the tobacco scrap in a uniform layer past and in contact with a plurality of rolls having a surface adapted to pick up such foreign material from the tobacco scrap, and stirring the tobacco scrap between the successive rolls to bring a new surface into position for the roll action.

4. In an apparatus for removing the foreign material such as shreds, fiber, etc., from tobacco scrap, the combination with a support for a layer of tobacco scrap, of one or more rolls having a surface adapted to pick up such foreign material, means for maintaining the proper distance between the scrap and roll surfaces by relative movement of the roll and scrap away from each other as the layer of foreign material on the roll increases in thickness, and means for rotating the rolls over the surface of the tobacco scrap.

5. In an apparatus for removing the foreign material, such as shreds, fiber, etc., from tobacco scrap, the combination with a support for a layer of tobacco scrap, of a plurality of rolls having a surface adapted to pick up such foreign material, means for rotating the rolls over the surface of the tobacco scrap, and means for stirring the tobacco scrap between the successive rolls to bring a fresh surface into position for the roll action.

6. In an apparatus for removing the foreign material, such as shreds, fiber, etc., from tobacco scrap, the combination with a traveling table or belt, of one or more rolls mounted to rotate in contact with tobacco scrap carried by the table, said rolls having surfaces adapted to pick up such foreign material and being free to move away from the table as the layer of foreign material increases in thickness.

7. In an apparatus for removing the foreign material, such as shreds, fiber, etc., from tobacco scrap, the combination with a traveling table or belt, of a plurality of rolls mounted to rotate in contact with tobacco scrap carried by the table, said rolls having surfaces adapted to pick up such foreign material and being free to move away from the table as the layer of foreign material increases in thickness, and stirrers between the rolls for bringing a fresh surface into position for the roll action.

In testimony whereof, we have hereunto set our hands, in the presence of two subscribing witnesses.

HOWARD G. BROCKWELL.
LEWIS W. HENDERSON.
